DUPLICATING ATTACHMENT FOR
TYPEWRITERSCharles S. Engleman, New York, N. Y., assignor
of one-half to Simon Metrik, New York, N. Y.

Application August 20, 1938, Serial No. 225,981

11 Claims. (Cl. 197—153)

This invention relates to typewriting machines and more particularly to machines having at least two ribbons whereby one of said ribbons may be used in the ordinary manner and both of said 5 ribbons may be used to obtain original and duplicate typewritten sheets.

While the duplicating mechanism herein contemplated may be incorporated in a typewriter as standard equipment, a feature of the invention resides in designing said duplicating mechanism in a manner adapting it as an attachment 10 for typewriters and capable of easy and quick assembly with and removal from such machines.

The invention further resides in the simplicity of construction of the duplicating mechanism; in the practical manner of mounting the duplicating ribbon and its spools; in the provision of a demountable and replaceable shield for said duplicating ribbon; in the combination and 20 cooperation between the typewriter parts and the duplicating mechanism for attaining efficient operation; and in the fact that no change or alteration of the typewriter mechanism is necessary when the duplicating mechanism is applied.

Other features of the invention reside in the manner of mounting the attachment upon a typewriter whereby said attachment may be swung out of use; in means incorporated in the 30 attachment for raising the duplicating ribbon for easier insertion between sheets that are being fed to the machine; and in the cooperative arrangement between the typewriter pressure rolls and release and clamping means for the duplicating ribbon.

With the foregoing and many other features, objects, and advantages in mind the invention resides in the combination and arrangement such as shown in the accompanying drawings in 40 which an exemplary form of the invention is illustrated.

The following specification based on said drawings, describes the invention in greater detail.

In the drawings:

Fig. 1 is a plan view, partly broken, of a typewriter incorporating mechanism as herein contemplated.

Fig. 2 is an enlarged fragmentary front view of the means for guiding the duplicating ribbon and mounting the shield therefor.

Fig. 3 is a sectional view as taken on the line 3—3 of Fig. 1 and to a scale somewhat greater than that of Fig. 1.

Figs. 4 and 5 are greatly enlarged fragmentary 5 sectional views of the typewriter platen together

with the two ribbons used in the invention and showing the relation of said ribbons and typewriter sheets before and during typing.

Referring to the drawings, the typewriter is provided in the usual manner with a frame 16 and with a carriage 11, said carriage including a roller platen 12, and a swingable frame 13 mounting the pressure rolls 14. At the rear thereof, the carriage is provided with a cross tie member 15.

The machine includes a pair of ribbon spools 23a mounted on the frame for the typewriter ribbon 22a which is supported and guided in the proximity of the platen in the usual manner, said spools being intermittently driven by the typewriter mechanism.

The foregoing is descriptive of a usual form of typewriter and details those parts which cooperate with the attachment herein contemplated for giving the operation sought.

The attachment comprises a frame 16 formed by the arms 17 and the connecting members 18, said arms being mounted on the cross tie 15 so the frame may be swung about said cross tie. The forward ends of the arms 17 are curved as at 19 to fit around the platen 12, each of the curved portions terminating in a short straight end portion 20.

Each arm 17 carries means such as the guide rolls 21 for a duplicating ribbon 22 stretched between said guide rolls and wound on the spools 23. The latter are mounted to move with the spools 23a, said mounting means, as shown, comprising a spider 24 mounted on each spool 23a and having an axial stud 25 passing through each spool 23, the stud being provided with a nut 26 for locking each of said spools 23 to each respective spider 24 and thus to its respective spool 23a. A drag such as the leaf spring 27 may be provided to engage the peripheral edge of each of the spools 23.

Each arm 17 is also provided with a vertical pin-like member 29a upon which is looped one end of a shield or guard tape 28 stretched along the duplicating ribbon at the front thereof. The free end of each pin-like member 29a is caught by a hook 29 also carried by its respective arm 17.

Because of the relative movement of the operative part of the duplicating ribbon and the spools 50 thereof, it is desired to lock said operative part against inadvertent endwise slippage when the machine is being fed with paper. For this purpose a finger 30 is pivotally mounted at 31 on each arm 17, said finger being urged to press the 55

duplicating ribbon 22 against the straight end portion 20 of the arm 17 by means such as the spring 32.

The above condition holds when the pressure roll frame 13 is lifted to facilitate feeding paper to the machine. When this is accomplished, however, the frame 13 is replaced to put the rolls 14 in contact with the paper mounted platen, and a portion of said frame is arranged to engage an extension 33 of the finger 30 to counteract the force of the spring 32 to lift said finger from contact with the duplicating ribbon. Hence said ribbon is freed to be moved by movement of the spools.

In order to expedite feeding of the paper to the machine, it is desirable to raise the duplicating ribbon and its guard tape and yet leave the hands free to accomplish the paper feeding. To this end the frame 16 is provided with a cross member 24 pivoted to the frame arms 17 at 35, and provided with one or more offset portions 36 adapted to lie flat against the platen when the frame and its ribbon are in the low position.

In order to raise the ribbon and its guard out of operative position so that a single copy may be made, a handle extension 37 of the cross member 34 may be swung to bring the offset portions 36 thereof in right angular engagement with the surface of the platen 12. This condition is shown by the dotted lines of Fig. 3.

With the duplicating ribbon and its guard so raised, it is a simple matter to feed two sheets of paper to the machine, one being fed between the platen and the ribbon and guard and the other outside said ribbon and guard as shown in Fig. 4 by the respective sheets A and B.

Now, as best seen in Fig. 5, when a type bar 38 strikes the ribbon 22a, an impression will be made on the sheet B from said ribbon 22a and an impression will be made on sheet A from the duplicating ribbon 22, the guard tape 28 serving to prevent the rear surface of sheet B from being inked by the latter ribbon.

If a third ribbon typed copy is desired, the guard tape 28 may be easily removed as indicated and a transparent sheet, preferably "onion skin" may be fed to the machine between the duplicating ribbon and the outer sheet B. Thus said duplicating ribbon will print upon the rear of the "onion skin" also, said printing being readable from the unprinted side of said sheet. Hence either two or three ribbon type copies may be obtained in an efficient manner.

From the foregoing it may be readily seen that a simple and efficient mechanism has been provided for the purpose intended. However, despite its simplicity, the mechanism may be modified within the spirit and scope of the invention as claimed.

Having thus described my invention, what I claim as new and desire to secure by Letters Patent, is:

1. In a typewriting machine having a carriage supporting a platen and having a typewriter ribbon and a pair of spools therefor, in combination, a second ribbon, spools for said second ribbon mounted respectively on the first mentioned spools and movable therewith, a swingable frame mounted on said carriage, and means on said frame for guiding said second ribbon.

2. In a typewriting machine having a carriage supporting a platen and a swingable frame having pressure rolls for contact with said platen and having a typewriter ribbon and a pair of spools therefor, in combination, a second ribbon,

spools for said second ribbon mounted respectively on the first mentioned spools and movable therewith, a second swingable frame mounted on said carriage, means on said second frame for guiding said second ribbon, and means for clamping said ribbon during feeding of paper to the machine, said clamping means being disengageable from said ribbon by the first mentioned frame.

3. In a typewriting machine, a duplicating ribbon, a pair of spools for said ribbon respectively mounted upon the ribbon spools of the machine, a swingable frame carried by the carriage of the machine, means on said frame for guiding said ribbon parallel to the platen of said machine, and means carried by said frame and having contact with said platen for maintaining said frame in raised position during feeding of paper to the machine.

4. In a typewriting machine, a duplicating ribbon, a pair of spools for said ribbon respectively mounted upon the ribbon spools of the machine, a swingable frame carried by the carriage of the machine, means on said frame for guiding said ribbon parallel to the platen of said machine, a guard tape carried by said frame in front of said ribbon, and means carried by said frame and having contact with said platen for maintaining said frame and said ribbon and guard tape in raised position during feeding of paper to the machine.

5. A duplicating attachment for typewriting machines comprising a frame adapted to be raised and lowered in relation to the platen of said machine, means for maintaining said frame in raised position during feeding of paper to said machine, a duplicating ribbon, means on said frame for guiding said ribbon along the longitudinal surface of said platen, a pair of spools for said ribbon, and means for mounting said spools on the respective spools of the machine for movement therewith.

6. A duplicating attachment for typewriting machines comprising a frame adapted to be raised and lowered in relation to the platen of said machine, means for maintaining said frame in raised position during feeding of paper to said machine, a duplicating ribbon, means on said frame for guiding said ribbon along the longitudinal surface of said platen, a guard tape carried by said frame and disposed along the front of said ribbon, a pair of spools for said ribbon, and means for mounting said spools on the respective spools of the machine for movement therewith.

7. In a typewriting machine, a duplicating ribbon, a pair of spools for said ribbon respectively mounted upon the ribbon spools of the machine, a swingable frame carried by the carriage of the machine, means on said frame for guiding said ribbon parallel to the platen of said machine, a translucent guard tape carried by said frame in front of said ribbon, and means carried by said frame and having contact with said platen for maintaining said frame and said ribbon and guard tape in raised position during feeding of paper to the machine.

8. A duplicating attachment for typewriting machines comprising a frame adapted to be raised and lowered in relation to the platen of said machine, means for maintaining said frame in raised position during feeding of paper to said machine, a duplicating ribbon, means on said frame for guiding said ribbon along the longitudinal surface of said platen, a guard tape of silk-like material carried by said frame and disposed along the front of said ribbon, a pair of

spools for said ribbon, and means for mounting said spools on the respective spools of the machine for movement therewith.

9. In a typewriting machine having a carriage supporting a platen and having a typewriter ribbon and a pair of spools therefor, in combination, a second ribbon, spools for said second ribbon mounted respectively on the first mentioned spools and movable therewith, a swingable frame mounted on said carriage, means on said frame for guiding said second ribbon, and means for clamping said second ribbon during feeding of paper to the machine, said clamping means being disengageable from said

15 second ribbon.

10. In a typewriting machine having a carriage supporting a platen and having a typewriter ribbon and a pair of spools therefor, in combination, a second ribbon, spools for said second ribbon mounted respectively on the first mentioned spools and movable therewith, means for exerting a drag on at least one of said spools

for said second ribbon, a swingable frame mounted on said carriage, means on said frame for guiding said second ribbon, and means for clamping said second ribbon during feeding of paper to the machine, said clamping means being disengageable from said second ribbon. 5

11. In a typewriting machine having a carriage supporting a platen and a swingable frame having pressure rolls for contact with said platen and having a typewriter ribbon and a pair of spools therefor, in combination, a second ribbon, spools for said second ribbon mounted respectively on the first mentioned spools and movable therewith, means for exerting a drag on at least one of said spools for said second ribbon, a second swingable frame mounted on said carriage, 10 means on said second frame for guiding said second ribbon, and means for clamping said ribbon during feeding of paper to the machine, said clamping means being disengageable from said 15 ribbon by the first mentioned frame. 20
